UNITED STATES PATENT OFFICE.

FRANK C. DORMENT, OF DETROIT, MICHIGAN, ASSIGNEE TO WIRELESS VIBRATOR COMPANY, OF DETROIT, MICHIGAN, A CORPORATION OF MICHIGAN.

VIBRATOR.

1,064,716.

Specification of Letters Patent. Patented June 17, 1913.

Application filed April 5, 1913. Serial No. 759,211.

To all whom it may concern:

Be it known that I, FRANK C. DORMENT, a citizen of the United States of America, residing at Detroit, in the county of Wayne and State of Michigan, have invented certain new and useful Improvements in Vibrators, of which the following is a specification, reference being had therein to the accompanying drawings.

10 This invention relates to a vibrator adapted for self treatment and arranged either for direct application to the body of the user or for vibrating the chair, stool or other support on which the subject may be.

15 The invention includes adjustments whereby the character and direction of the vibrations may be changed together with other features which insure its easy manipulation.

The invention consists in the matters hereinafter set forth and pointed out in the appended claims.

In the drawings, Figure 1 is a view in elevation of a vibrator that embodies features of the invention showing it attached to a chair or the like; Fig. 2 is a view in elevation taken at right angles to Fig. 1; Fig. 3 is a view in detail of an adjustable yoke; and Fig. 4 is a view in detail showing one form of a massage member.

30 As herein shown in preferred form a slide rod 1 is frictionally held at one end in one socket 2 of a combined handle and counter-weight 3. The angle of adjustment of the slide to the handle may be varied by shifting the slide to another socket if desired, such sockets being arranged to give the necessary oblique relation between the parts. The handle is arranged to be adjustably secured on a pivot stud 4 which passes through the 35 body of a clamp 5, meeting serrated faces indicated at 6 affording angular adjustment of the parts and a suitable thumb screw or binding nut 7 holding them in adjusted position. If it is desired to pivotally support the slide rod, the handle may be reversed in 40 position as indicated by the dotted lines at 8, in which instance its serrated face bears against the plane face on the hub and permits the handle to swing on the bolt.

50 A member for conveying any vibrations imparted to the slide is attached to the outer end thereof. This may take any desired form, such for example, as that indicated

at 9 which is provided with sockets 10 and set screw 11 common to all, whereby it may be clamped in any desired position.

A metal strip is bent upon itself to form a U-shaped yoke having parallel arms 12 that are connected by a bridge 13 at their outer ends and are apertured to move longitudinally on the rod 1. A pair of parallel vibrating rods 21 pass through guide apertures in the bend of the yoke and are secured as by riveting or the like to the bridge 13. A friction roller 14 is journaled on a cross piece 15 which is in sliding engagement with the rods 21 and is projected against the slide member 1 by suitably disposed springs 16 which may preferably be in compression between the bend of the yoke and the cross-piece which may preferably be retained by the rods 21 as keepers. The yoke preferably has roughened faces as indicated at 17 to afford suitable finger grip. A bar 18 with curved spring 19 is adjustable longitudinally on the rods 21.

The clip 5 is arranged to be secured to a chair 20 or the like and also has one or more sockets into which the rod 1 may be inserted and held frictionally if desired, to use without the handle.

The device is operated by grasping the finger grip of the yoke and moving it up and down the slide rod, the resultant vibrations of the free ends of the rods extending from the yoke being communicated to the slide rod. If one end of the slide rod is inserted in the handle and held by the user, a massage member on the other end of the slide rod may be pressed against any portion of the body of the user to impart the vibrations of the slide rod thereto. Or the slide rod may be mounted either directly or indirectly in the clamp and the massage member applied as before when the slide rod is vibrated by manipulation of the yoke. If the slide rod be secured in the clamp and the comparatively heavy handle be attached to the other end of the slide rod in place of the massage member, manipulation of the yoke results in the vibration of the chair or other support to which the clamp is attached. As the angle of inclination of the slide rod may be altered, the character or direction of the effect of the vibrations may be correspondingly changed. The rapidity

of the vibrations may be changed by shifting the cross-piece in or out on the two vibrating rods attached to the yoke.

The device while simple is effective in producing vibrations of any desired frequency within the range of the operation of the apparatus. The friction roll held yieldingly by the springs in contact with the slide compensates for any wear between the slide and yoke and keeps the parts always in such operative relation that they produce the desired effect. The device may be easily cleaned and is not liable to disarrangement.

15 Obviously, changes in the details of construction may be made without departing from the spirit of my invention and I do not care to limit myself to any particular form or arrangement of parts.

20 What I claim is:—

1. A massaging vibrator comprising a handle, a slide rod adapted to be adjustably secured therein, means for fixing the handle in desired angular position, a yoke having arms in sliding engagement with the rod, spring pressed means in the yoke for preventing slack between the arms and the slide rod, and a pair of vibrating rods extending from the yoke.

2. A massaging vibrator comprising a slide rod, a yoke having arms provided with guide apertures through which the slide rod passes, spring pressed means in the yoke bearing against the slide rod for preventing slack between the latter and the yoke arms and a pair of vibrating rods secured to the yoke to extend transversely to the slide rod.

3. A massaging vibrator comprising a slide rod, a handle for adjustably securing the slide rod at one end, means for clamp-

ing the handle at any desired angle, a pair of vibrating rods transverse to the slide rod, a yoke to which the vibrating rods are secured, adapted to move longitudinally on the slide rod and yielding means for maintaining the slide rod and yoke in operative relation.

4. A massaging vibrator comprising a slide rod, a U-shaped sheet metal yoke whose arms are in sliding engagement with the slide rod, a bridge connecting the yoke arm ends, a pair of parallel vibrating rods passing through the bend of the yoke and attached to the bridge, a cross piece sliding on the vibrating rods, a friction roller on the cross piece adapted to bear against the slide rod and springs on the vibrating rods for projecting the cross piece and roller against the slide rod.

5. A massaging vibrator comprising a clamp, a weighted handle angularly adjustable on the clamp, a slide rod adjustably secured at one end to the handle, a U-shaped metal strip having parallel apertured arms in sliding engagement with the slide rod, a bridge connecting the arms at the ends thereof a pair of vibrator rods secured to the yoke, a cross piece sliding on the rods within the yoke, a friction roller on the cross piece, springs on the rods for projecting the roller against the slide rod and a weight bar adjustable longitudinally on the vibrator rods.

In testimony whereof I affix my signature in presence of two witnesses.
